LLP; D. Scott Hemingway

(57) **CLAIM**

The ornamental design for a canteen measuring tape holder
with nozzle and cap, as shown and described.

DESCRIPTION

FIG. 1 is a front perspective view of my new canteen measuring tape holder with nozzle and cap with an elevated and exploded cap view;

FIG. 2 is a front elevation view of my new canteen measuring tape holder with nozzle and cap with an elevated and exploded cap view;

FIG. 3 is a rear elevation view of my new canteen measuring tape holder with nozzle and cap with an elevated and exploded cap view;

FIG. 4 is a right side view of my new canteen measuring tape holder with nozzle and cap with an elevated and exploded cap view;

FIG. 5 is a left side view of my new canteen measuring tape holder with nozzle and cap with an elevated and exploded cap view;

FIG. 6 is a top view of my new canteen measuring tape holder with nozzle and cap with an elevated and exploded cap view;

FIG. 7 is a bottom view of my new canteen measuring tape holder with nozzle and cap with an elevated and exploded cap view;

FIG. 8 is a front perspective view of my new canteen measuring tape holder with nozzle and cap with an attached cap view;

FIG. 9 is a front elevation view of my new canteen measuring tape holder with nozzle and cap with an attached cap view;

FIG. 10 is a rear elevation view of my new canteen measuring tape holder with nozzle and cap with an attached cap view;

FIG. 11 is a right side view of my new canteen measuring tape holder with nozzle and cap with an attached cap view;

FIG. 12 is a left side view of my new canteen measuring tape holder with nozzle and cap with an attached cap view;

FIG. 13 is a top view of my new canteen measuring tape holder with nozzle and cap with an attached cap view; and,

FIG. 14 is a bottom view of my new canteen measuring tape holder with nozzle and cap with an attached cap view.

The broken lines depict portions of the canteen measuring tape holder with nozzle and cap that form no part of the claimed design.
